REUSABLE COFFEE-FILTER

Werner Braun, Sarnen, Switzerland, assignor to
Interelectric Aktiengesellschaft

Filed Aug. 15, 1973, Ser. No. 388,555

Claims priority, application Germany Feb. 19, 1973

Term of patent 14 years

Int. Cl. D7—04

U.S. Cl. D7—47

Fig. 4

Fig. 1

Fig. 2

Fig. 3

FIG. 1 is a side elevational view of a reusable coffee-filter showing my new design, the opposite side being a mirror image;

FIG. 2 is another side elevational view of the reusable coffee-filter shown from the right hand side of FIG. 1;

FIG. 3 is a top plan view of the reusable coffee-filter; and

FIG. 4 is a bottom plan view of the reusable coffee-filter.

I claim:

The ornamental design for a reusable coffee-filter, as shown and described.
